UNITED STATES PATENT OFFICE

2,593,580

SPRING COIN HOLDER

Joseph Loevenich, New York, N. Y.

Application May 17, 1948, Serial No. 27,481

1 Claim. (Cl. 133—6)

1

This invention relates to coin holders.

An object of this invention is to provide a coin holder which includes a magazine of flat formed with at least one opening in one end thereof through which coins or tokens may be inserted or removed, the coins or tokens being held in the holder by means of a pair of spring fingers.

Another object of this invention is to provide a coin holder embodying a housing formed with a restricted mouth and a pair of spring coin-retaining fingers integral with the housing for releasably holding coins in the holder.

A further object of this invention is to provide a holder of this kind which may be stamped out of sheet metal, the parts forming the holder being soldered or otherwise secured together in telescoping position.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawing:

Figure 1 is a detailed rear elevation of a coin holder constructed according to an embodiment of this invention.

Figure 2 is a detailed side elevation of the device.

Figure 3 is a sectional view, partly broken away, taken on the line 3—3 of Figure 1.

Figure 4 is an enlarged fragmentary sectional view taken on the line 4—4 of Figure 3.

Figure 5 is a transverse sectional view, partly broken away, taken on the line 5—5 of Figure 1.

Figure 6 is a plan view of the blank for the rear portion of the holder.

Figure 7 is a plan view of the blank for the front portion of the holder.

Referring to the drawing, the numerals 10 and 11 designate generally a pair of telescoping housing members which are secured together as by soldering or the like. The housing member 10 is of elongated configuration and includes an elongated plate 12 which at its rear end is formed with a right-angular end flange 13. The plate 12 is provided along the lengthwise edges thereof with right-angular side flanges 14 and the flanges 14 at their forward ends are curved inwardly as indicated 15 so as to thereby provide a mouth 16 at the forward end of the holder.

The plate 12 is also formed at its forward end

with a curved coin engaging seat 17 which is formed with a convex outer edge 18. The housing member 11 includes an elongated plate 19 which at its upper or rear end is formed with 5 a right-angular flange 20 and is formed on its lengthwise edges with right-angular flanges 21. The flanges 20 and 21 telescope into the flanges 13 and 14 and are secured by tongues or other fastening means 22. The plate 19 is formed with 10 a forwardly projecting curved forward end 23 having a concave cutout 24 which forms a finger recess whereby a coin C engaging in the mouth 16 may be engaged by a thumb or finger so as to withdraw the coin from the holder. The side 15 flanges 21 of the housing member 11 are also formed with a pair of bowed integral spring fingers 25 which are reversely bowed as at 26. The fingers 25 are adapted to project into the mouth 16 for resiliently retaining the coin C in 20 the mouth and each finger 25 is formed with a pair of detents 30 which prevent the fingers from catching on the forward end of wall 19 of housing 11.

The holder comprising the complementary 25 housing members 10 and 11 may have a suitable supporting means secured to the rear or inner housing member 11 and in the present instance a safety pin 27 is secured to the plate 19 adjacent the upper end thereof. It will be understood that any suitable securing or supporting means 30 may be provided for attaching or supporting the holder. A conventional safety pin 27 is herein disclosed as one form of fastening and supporting means for the holder. The housing members 10 and 11 are provided with aligned holes 28 and 29 for receiving a ring in lieu of the safety pin, or if desired, a spring clip such as are used on pens and pencils may be used.

In the use and operation of this device the 40 coins or tokens are inserted into the holder comprising the housing members 10 and 11 through the mouth 16, the spring fingers 25 being pressed outwardly by inward movement of the coin. When the holder is disposed in upright position 45 with the mouth 16 thereof lowermost, the foremost coin in the holder will drop down toward the mouth, projecting partly into the mouth 16 and being retained in a position for removal by the spring fingers 25. The coin may be removed 50 by pressing the thumb or a finger against the exposed portion of the coin C in the cutout 24 and pulling the coin forwardly or downwardly.

This holder is, as herein disclosed, formed out 55 of two flat pieces of sheet metal which are stamped out and then secured together by suit-

able fastening means. It will be understood that this holder may be designed with a coin opening at each end or as a multiple housing assembly wherein two or more housings are superposed one on the other so that coins of different denominations may be dispensed.

I claim:

A coin holder comprising a housing including a pair of spaced apart elongated flat plates, right angular flanges formed along the opposite longitudinal edges of one of said plates with the end portions thereof curved inwardly to form a mouth, the other of said plates being formed with right angular flanges along the major portion of the opposite longitudinal edges thereof, said latter flanges engaging within said first mentioned flanges, an inwardly bowed resilient retaining finger formed integral with one end of each of the flanges on said other plate said other plate having a cut away portion between said resilient retaining fingers and the adjacent portion of the plate, said retaining fingers being disposed inwardly of said mouth forming curved portions, and a plurality of transverse inwardly

10

5

extending beads formed in each of said retaining fingers adapted to overlie the adjacent longitudinal edges of said other plate when said retaining fingers are sprung outwardly to their fullest extent against said curved flange portions whereby said fingers are prevented from being caught on said adjacent longitudinal edges.

JOSEPH LOEVENICH.
